UNITED STATES PATENT OFFICE.

JOHN A. ZUBLIN, OF LOS ANGELES, AND WILLARD L. BOROUGH, OF FULLERTON, CALIFORNIA; SAID BOROUGH ASSIGNOR TO SAID ZUBLIN.

RECIPROCATING PUMP WITH INDIVIDUAL JOINTS BETWEEN PLUNGERS.

Application filed February 13, 1924. Serial No. 692,514.

Our present invention relates to reciprocating pumps especially suitable for use in deep wells, such as oil wells, and more particularly to pumps comprising separate short 5 plungers or plunger sections, each provided with a valve and all cooperating with a common cylinder or barrel, or with replaceable or sectional liners retained in such a cylinder or barrel; and it is an especial object of this 10 invention to provide a pump whose reciprocating plunger sections are connected by novel individual joints permitting both a pivotal and a sliding movement therebetween in a manner favorable to easy and effective operation and to the avoidance of undue strain or wear.

It is already recognized that an ordinary one-piece plunger, as heretofore commonly used, is liable to become defective in operation by reason of failure to obtain or to maintain an all-around fit, or because of adverse conditions of temperature and pressure, during use, tending to produce distortions and to cause eccentric wear. In view 25 of the conditions referred to, sectional liners have become popular and the Zublin pump has been introduced; and our present improvement is especially suitable for use in connection with multistage pumps of the Zublin type, or in connection with other reciprocating, heavy-duty pumps, whether using sectional or unitary liners.

It is an object of this invention to increase the efficiency and prolong the life of pumps comprising two or more short plungers or plunger sections by joining the mentioned short plungers or plunger sections in a manner favorable to an independent automatic centering of each section within a barrel or liner section, thereby minimizing side throw and eccentric wear; and our preferred means for this purpose may comprise transverse pins or heads or other connecting elements extending through slots or other openings 45 sufficiently large to permit of either a relative pivotal movement or a lateral offsetting movement, or any suitable combination of pivotal and offsetting movements, as may be required to enable the respective sections to 50 adjust themselves independently, during their operation, into positions coaxial with the cylindrical element within which each may, at any given time, be moving.

Other objects of our invention will appear 55 from the following description of an illus-

trative embodiment thereof, taken in connection with the appended claims and the accompanying drawings, in which

Fig. 1 is an elevational view of a pump embodying our invention, with parts sectioned or broken away.

Fig. 2 is an enlarged detail sectional view showing one advantageous mode or means of connecting a pair of short plungers or plunger sections.

Figs. 3 and 4 illustrate an alternative form in which threaded hinge elements, by which a pair of plungers or plunger sections are connected, serve also as means for the retention of valve seats. Fig. 4 is taken in a 70 plane at right angles to that represented in Fig. 3, and on a slightly larger scale.

Referring to the details of that specific embodiment of our invention shown in Fig. 2, 1 may be a pump barrel, connected in the 75 manner suggested in Fig. 1, or in any preferred manner, to a string of pipe, and 2 may be a sectional or other liner therein, the respective short plungers or plunger sections 3 being provided with valves of any suitable 80 character, not shown. Our invention involves the use of novel coupling or connecting means, such as the loosely interfitting and complementary hinge elements 4, 5, each of which may be provided with an exteriorly 85 threaded head 6, adapted to engage a corresponding interior thread 7, in a plunger section, any suitable channels 8 being provided to permit of a free relative movement of oil or other liquid pumped; and the projecting 90 portions of the respective hinge members 4 and 5 may be provided with transverse circular or non-circular apertures 9 and 10 adapted loosely to receive a transverse connecting member such as the pin 11, shown as retained by means of cotters 12, extending through the opposite ends thereof. In order to permit of not only a pivotal movement between the hinge elements 4 and 5, but also of a sliding movement therebetween, it is important 95 that, as diagrammatically shown in the drawing, ample clearance should be left not only between the interfitting projections engaged by the pin 11, but also between the latter element and the walls surrounding the 100 same.

Referring to the specific embodiment of our invention shown in Figs. 3 and 4, an outer barrel being shown at 1', and liner sections being shown at 2', the plungers or 110

plunger sections 3' are shown as connected by hinge elements 4', 5' of a slightly more complex structure adapting the same to serve not only as connecting means, but as 5 means for the retention of valve seats 13, 13'.

As before, the heads 6' may be exteriorly threaded to engage interior threads 7 within the respective plunger sections, and a pair of 10 such threaded heads may be utilized, as is well illustrated in Fig. 4, in the retention of a valve seat, such as the reversible and replaceable valve seat 14, adapted to receive a ball 15; and one of the hinge sections 6 15 may then serve as a cage for the retention of such a ball.

In the form of our invention shown in Figs. 3 and 4, we may employ a transverse pin 11' rigidly connected with one of the 20 mentioned hinge elements, as by forming the said pin integral with a threaded body 16, shown as adjustable within a lower hinge element 5' and as retained against rotation therein by means of a rivet 17. When we 25 employ such a construction as is here referred to, it will be obvious that the pin 11' may have either a sliding or a pivotal engagement, or both a sliding and a pivotal engagement, upon shoulders 18 defining the 30 passage 9' within which said pin is freely movable.

Although we have herein described two advantageous embodiments of our invention, it will be understood that important advantages of our invention might be obtained by any alternative type of loose pivotal connection between a pair or series of short plungers or plunger sections adapted for reciprocation within a barrel or liner or 35 liner sections; and it will also be obvious that various features of our invention might be independently employed.

We claim as our invention:

1. A reciprocating pump comprising: a 45 plurality of plungers disposed endwise to each other; and means for loosely connecting said plungers together, said means functioning additionally as a valve cage.

2. A reciprocating pump comprising: a 50 plurality of comparatively short plungers disposed endwise to each other and close together; and means connecting said plungers and permitting movements of each plunger relative to the other plungers, said means 55 functioning additionally as a valve cage.

3. A reciprocating pump comprising: a

plurality of comparatively short hollow plungers disposed endwise to each other; a valve for each plunger; and means loosely connecting said plungers together, said means functioning additionally as a valve cage. 60

4. A reciprocating pump comprising: a plurality of hollow plungers disposed endwise to each other and close together; a valve 65 for each of said plungers; and means loosely connecting said plungers, said means functioning additionally as a valve cage.

5. In a reciprocating pump, the combination of: a plurality of plungers hingedly 70 connected by means permitting a lateral or offsetting movement between said plungers; and a valve seat, said valve seat being retained in place by said means.

6. A reciprocating pump comprising: a 75 plurality of plungers disposed endwise to each other; means for loosely connecting said plungers together, said means functioning additionally as a valve cage; and a valve seat, said valve seat being retained in place 80 by said means.

7. A reciprocating pump comprising: a plurality of comparatively short plungers disposed endwise to each other and close together; means connecting said plungers and 85 permitting movements of each plunger relative to the other plungers, said means functioning additionally as a valve cage; and a valve seat, said valve seat being retained in place by said means. 90

8. A reciprocating pump comprising: a plurality of comparatively short hollow plungers disposed endwise to each other; a valve for each plunger; means loosely connecting said plungers together, said means 95 functioning additionally as a valve cage; and a valve seat, said valve seat being retained in place by said means.

9. A reciprocating pump comprising: a plurality of hollow plungers disposed end- 100 wise to each other and close together; a valve for each of said plungers; means loosely connecting said plungers, said means functioning additionally as a valve cage; and a valve seat, said valve seat being retained in 105 place by said means.

In testimony whereof, we have hereunto set our hands at Los Angeles, California, this 7th day of February, 1924.

JOHN A. ZUBLIN.
WILLARD L. BOROUGH.
